CLAIM

The ornamental design for a toilet seat for children as shown and described.

DESCRIPTION

FIG. 1 is a front, right and top perspective view of a toilet seat for children, showing my new design.

FIG. 2 is a rear, left and bottom perspective view of the toilet seat for children.

FIG. 3 is a front elevation view of the toilet seat for children.

FIG. 4 is a rear elevation view of the toilet seat for children.

FIG. 5 is a left side elevation view of the toilet seat for children.

FIG. 6 is a right side elevation view of the toilet seat for children.

FIG. 7 is a top plan view of the toilet seat for children; and, FIG. 8 is a bottom plan view of the toilet seat for children. The dashed broken lines depict portions of the toilet seat for children that form no part of the claimed design.

1 Claim, 8 Drawing Sheets
